UNITED STATES PATENT OFFICE.

GEORGE R. FOX, OF PLAQUEMINE, LOUISIANA.

DESIGN FOR A BRUSH.

SPECIFICATION forming part of Design No. 29,883, dated December 27, 1898.

Application filed December 2, 1898. Serial No. 698,114. Term of patent 14 years.

To all whom it may concern:

Be it known that I, GEORGE R. FOX, a citizen of the United States, residing at Plaquemine, in the parish of Iberville and State of Louisiana, have invented and produced a certain new and original Design for Brushes; and I do declare the following to be a full, clear, and exact description of the invention, such as will enable others skilled in the art o to which it appertains to make and use the same.

The invention relates to a new and original design for a brush; and it consists of a brush of the configuration shown in the accompanying drawings, in which—

Figure 1 is a perspective view of the brush, and Fig. 2 is a cross-sectional view.

The leading features of the design consist in the head of the brush of the shape shown, having longitudinal grooves in its sides, tufts 20 of bristles projecting from its face, and the longitudinal curved toothed rib projecting from its back.

What I claim is—

The design for a brush as herein shown and 25 described.

In testimony whereof I have hereunto set my hand in presence of two subscribing witnesses.

GEORGE R. FOX.
